CLAIM

The ornamental design for a fender for work vehicle, as shown and described.

DESCRIPTION

FIG. 1 is a rear perspective view of a fender for work vehicle according to one embodiment of our new design;

FIG. 2 is a front perspective view thereof;

FIG. 3 is a front elevation view thereof;

FIG. 4 is a rear elevation view thereof;

FIG. 5 is a first side elevation view thereof;

FIG. 6 is a second side elevation view thereof;

FIG. 7 is a top plan view thereof;

FIG. 8 is a bottom plan view thereof;

FIG. 9 is a rear perspective view of a fender for work vehicle according to another embodiment of our new design;

FIG. 10 is a front perspective view thereof;

FIG. 11 is a front elevation view thereof;

FIG. 12 is a rear elevation view thereof;

FIG. 13 is a first side elevation view thereof;

FIG. 14 is a second side elevation view thereof;

FIG. 15 is a top plan view thereof; and,

FIG. 16 is a bottom plan view thereof.

The dashed lines in the figures depict environment subject matter that forms no part of the claimed design.
